(57) **CLAIM**

The ornamental design for a spare tire rack, as shown and described.

DESCRIPTION

FIG. 1 is a front, right, top perspective view of a spare tire rack, showing our design.

FIG. 2 is a rear, left, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view of an area labeled 9 in FIG. 1 comprising a connecting part; and,

FIG. 10 is a partial enlarged view of any area labeled 10 in FIG. 2 comprising an adjusting part.

The broken lines shown in the drawings are included for the purpose of illustrating portions of the spare tire rack that form no part of the claimed design.

1 Claim, 10 Drawing Sheets
